DESIGN FOR A BALL COCK BODY

Herbert D. Clemons, Sturgis, Mich., assignor
to Scovill Manufacturing Company, Sturgis,
Mich.

Application April 6, 1934, Serial No. 51,334

Term of patent 14 years

To all whom it may concern:

Be it known that I, HERBERT D. CLEMMONS, a citizen of the United States, residing at Sturgis, in the county of St. Joseph and State of Michigan, have invented a new, original, and ornamental Design for a Ball Cock Body, of which the following is a specification, reference being had to the accompanying drawing, forming part thereof, in which:

Fig. 1 is a side elevation,

Fig. 2 is an elevation looking from the right of Fig. 1,

Fig. 3 is an elevation looking from the left to Fig. 1, and

Fig. 4 is a top perspective view of a ball cock body, showing my new design.

I claim:

The ornamental design for a ball cock body, as shown.

HERBERT D. CLEMMONS.
